ATTORNEY

UNITED STATES PATENT OFFICE.

HENRY MILTON MONTGOMERY, OF CEDAR VALE, KANSAS.

ERASER.

1,249,989.

Specification of Letters Patent. Patented Dec. 11, 1917.

Application filed July 13, 1917. Serial No. 180,435.

To all whom it may concern:

Be it known that I, HENRY M. MONTGOMERY, a citizen of the United States, residing at Cedar Vale, in the county of 5 Chautauqua and State of Kansas, have invented new and useful Improvements in Erasers, of which the following is a specification.

This invention relates to improvements in 10 erasers for erasing pencil marks, ink or the like, or both, the object of the invention being to provide an improved eraser of this kind embodying a rubber core and a wooden sheathing which serves to cover all of the 15 rubber core excepting the ends and which protects the rubber core and prevents the same from becoming soiled, the said sheathing comprising a series of sections which may be readily split off one at a time from 20 the rubber core as the eraser is used and becomes worn, and which sheathing sections are arranged end to end and in contact with one another.

The invention consists in the construction, 25 combination and arrangement of devices hereinafter described and claimed.

In the accompanying drawings:—

Figure 1 is partly an elevation and partly 30 a sectional view of an eraser constructed and arranged in accordance with my invention.

Fig. 2 is a transverse sectional view of the same.

My improved eraser comprises a core 1 which is in the form of a strip or bar of 35 rubber and which may be of any suitable manufacture and adapted for use for erasing pencil marks or ink marks, or for both of such uses, as here shown, the end 2 of the rubber core being for erasing pencil

marks and the end 3 thereof for erasing 40 ink marks.

I also provide a sheathing 4 for the rubber core and through which the latter extends, the sheathing being made of suitable wood, such as cedar, and comprising a series of 45 sections 5, which sections are arranged end to end and are in mutual contact. The sheathing is secured on the rubber core by glue or the like and each section is narrowed toward each end so that each side or 50 wall of each section of the sheathing is thickened at the center and reduced in thickness toward the ends as at 6. The wooden sheathing stiffens the rubber, facilitates the use of the device as an eraser, and exposes 55 the ends of the rubber core while covering and protecting the intermediate portion thereof and preventing the same from becoming soiled or covered with or accumulating dirt.

From time to time as the rubber wears from use, a section of the sheathing, nearest the worn end of the rubber, may be split off to expose an additional portion of the rubber core for use.

Having thus described my invention, I claim:—

An eraser comprising a rubber core and a sheathing through which the core extends from end to end, the said sheathing covering the core excepting at the ends and comprising a series of sections, the said sections of the sheathing being arranged end to end and being separately removable from the core.

In testimony whereof I affix my signature.

HENRY MILTON MONTGOMERY.
